UNITED STATES PATENT OFFICE

MAURICE J. DU FEAU, OF MILWAUKEE, WISCONSIN

ELECTRICALLY-CONTROLLED RECEPTACLE CLOSURE

Application filed July 11, 1924. Serial No. 725,532.

The invention relates to electrically controlled closures for preventing unauthorized access to money deposit boxes or other receptacles.

5 An object of the invention is to provide a receptacle closure which is electrically controlled from a distance in order to gain access to the interior of the receptacle, whereby unauthorized entrance to the receptacle is 10 prevented.

Another object of the invention is to provide closure locking means in which a locking member is electromagnetically actuated for opening the closure and is held in locking 15 position against forcing by a second electromagnetically actuated locking means.

A further object of the invention is to provide an electromagnetically actuated closure which when open breaks the controlling 20 circuits.

A further object of the invention is to provide a receptacle having an electromagnetically actuated closure which opens to discharge the contents upon the establishment 25 of controlling circuits.

A further object of the invention is to provide means for effecting an alarm upon unauthorized manipulation of the closure or dis- 30 placement of the receptacle.

30 A further object of the invention is to perfect details of construction generally.

The invention further consists of the several features hereinafter set forth and more particularly defined by the claims at the conclusion hereof.

35 In the accompanying drawings: Fig. 1 is an elevation view of the money deposit box embodying the invention as incorporated in a suitable stand and adapted for receiving contributions in a church, parts of the box and stand being broken away and parts being shown in section;

40 Fig. 2 is a longitudinal sectional view of the money deposit box shown in Fig. 1;

45 Fig. 3 is an end view of the box;

Fig. 4 is a sectional view taken on the line 4—4 of Fig. 2, parts being broken away and parts being shown in section;

Fig. 5 is a sectional view taken on the line 5—5 of Fig. 2;

Fig. 6 is a sectional view taken on the line 6—6 of Fig. 5;

Fig. 7 is a sectional view taken on the line 7—7 of Fig. 5, but showing the closure in an open position;

Fig. 8 is a wiring diagram showing the controlling and alarm circuits;

Fig. 9 is a detail sectional view of the bottom of the stand and its electrical connections with the floor receptacle; and

Fig. 10 is a top view of the floor receptacle, parts being broken away.

In these drawings, 20 indicates a money deposit box mounted within a suitable stand 21 where it is adapted for use in receiving contributions in a church. The box 20 comprises a casing 22 having an opening 23 in its bottom normally closed by a closure plate 24 and mounted in the upper portion of the stand by angles 25 preferably adjacent an edge band 26 which is provided with a coin-receiving slot 27 disposed in register with a slot 28 in the upper portion of the casing.

The casing 22 is cast of suitable metal and is covered by hardened steel plates 29 to prevent drilling through or breakage by a blow. The plates are secured to the casing by countersunk screws 30 flowed over with metal to prevent their removal and the closure plate 24 is likewise protected by a plate 31 secured thereto by countersunk screws 32 and is mounted to swing in the casing by intermediately disposed aligned trunnions 33 journaled in the casing but concealed from the outside by the steel covering, as shown in Fig. 4.

In the present instance, I have shown the locking mechanism mounted on the closure plate. A locking bolt 34 is slidably mounted in spaced brackets 35 and 36, which are

50

mounted on the closure plate by countersunk screws 37 flowed over with metal to prevent removal. The locking bolt cooperates with a keeper 38 comprising a heavy flat spring having its upper end secured to the front wall of the casing and having its lower free end 39 projecting outwardly to receive the end of the bolt, which is beveled to pass the keeper on its upward movement.

10 An armature 40 is secured transversely of the locking bolt by a tongue 41 projecting from the former and fastened to the upper edge of the bolt by a screw 42, the tongue also serving to limit the forward movement 15 of the bolt by its abutment with the bracket 36.

The armature is disposed adjacent electromagnets 43 mounted in brackets 44 secured to the closure plate on either side of the locking bolt. When energized, the electromagnets retract the locking bolt under certain 20 conditions hereinafter set forth and permit the closure to swing open.

The rear end of the locking bolt is provided 25 with a transverse opening 45 to receive a locking pin 46 slidably mounted in the bracket 35, as seen in Fig. 4, when the bolt is in its locked position, thereby preventing any attempt to force the bolt.

30 The outer end of the locking pin 46 is pivotally connected to the lower end of the lever 47 pivotally mounted intermediate its ends on a bracket 48 secured to the closure plate. A rod 49 has one end pivotally connected to 35 the upper end of the lever and is slidably mounted in the upper part of the bracket 35 substantially parallel with the locking pin, all moving parts having a sufficiently loose fit to prevent binding.

40 The other end of the rod 49 is provided with an armature 50 which is disposed adjacent electromagnet 51 mounted on the bracket 35. The electromagnet when energized serves to attract the armature 50 and 45 through the linkage to retract the locking pin 46 out of the opening in the locking bolt to permit the latter to be moved by the electromagnet 43 in order that the closure plate 24 may be swung open. The locking pin is 50 retained in normally locked position by a spring 49' mounted over the rod 49 and urging it away from the electromagnet 51.

In order to connect the electromagnets with a source of current the bracket 35 is provided 55 with an insulating plate 32 in which are mounted spring plungers 53, 54 and 55, 56 having connections with the electromagnets 43 and 51 respectively.

When the receptacle is closed the spring 60 plungers 53, 54, 55 and 56 bear against contact members 57, 58, 59, 60, respectively, passing through the rear wall of the casing to form terminals and insulated therefrom.

A contact shoe 61 is adjustably secured to 65 the bracket 35 by a screw 62 and extends ad-

jacent an insulated contact member 63 in the casing, similar to contact members 57 to 60.

A grounding terminal 64 is secured to the casing at the other side of the rear wall, and when an attempt is made to force the closure plate, a slight inward movement of the plate at the forward end will establish contact between the grounded contact shoe 61 and the insulated contact member 63, and thereby effect an alarm circuit hereinafter described.

The stand is provided with a tubular support 65 in the bottom end of which an insulating plate 66 is inserted to receive spring pressed contact plungers 67 connected to the contact members or terminals, 57, 58, 59, 60, 63 and 64 in the casing by conductors 65, 66, 67, 68, 69 and 70, respectively. Choke coils or resistors 71 disposed in the stand may be introduced into the conductors 67 and 68 to limit the current flow through the electromagnet 51.

A floor receptacle 72 is provided to complete the control and alarm circuits and to permit the stand to be moved for cleaning or other purposes. The receptacle includes an insulating block 73 provided with upwardly projecting studs 74 entering the lower ends of openings 75 in a superimposed insulating block 76 secured thereto and to the casing of the receptacle by screws 77. The spring plungers 67 in the tubular support of the stand then enter the upper ends of the openings to engage the contact studs 74, these being preferably unsymmetrically arranged to insure connections of correct polarity.

A spring contact arm 78 is secured to the upper side of the insulating block 73 and has its free end normally depressed out of contact with a contact finger 79 by an adjustable screw 80 projecting downwardly from the insulating block 66 in the bottom of the tubular support 65 into engagement with a movable insulating button 81 pressing on the contact arm. The contact arm and finger are connected to the contact studs receiving conductors 69 and 70, respectively, which together with conductors 65 through 68 continue through the receptacle connection.

The conductor 67 is joined to the conductor 66 which then forms a common lead for supplying currents to both electromagnets. The conductor 65 for supplying current to the electromagnet 43 is connected to one blade of a double pole switch 82 while conductor 68 for supplying current to the electromagnet 51 is connected to the other blade. Contact clips 83 and 84 of the switch are connected together to a conductor 85 which with conductor 66 form the supply leads. The clip 83 is lower than the clip 84 so the one blade of the switch will make contact before the other to energize the electromagnet 51 before the electromagnet 43 is energized. As a result the locking pin 46 is withdrawn from the opening in the locking bolt 34, permitting the latter to be

withdrawn from the keeper 38 by the electro-magnet 43. The closure plate then swings downward on its trunnions and discharges the money into a basket 86 suspended below the box, whereupon the money may be removed. To avoid the noise and racking of parts, the pivoted closure plate swings down freely without hitting any stop.

To avoid interference with the mechanism by money deposited in the box through the slot 28, a shielding plate 87, preferably of insulating material is fastened to the armature 40 by screws 88 and extends adjacent the top of the casing to enclose the mechanism.

Conductors 69 and 70 form part of an alarm circuit including a bell 89 and a source of supply, which may be a transformer 90. An attempt to force the closure plate of the box will cause the contact arms 61 to engage the contact terminal 63 to close the alarm circuit, and the lifting of the support 65 off the floor receptacle will also close the circuit by the engagement of the contact arm 78 with the finger 79 when the pressure of the screw 80 is removed.

The controlling circuits are opened as the closure opens, so that the current flows only momentarily through the electromagnets. This feature also obviates the use of flexible connectors which are liable to break and cause difficulties in opening the closure.

While I have shown the electromagnetic actuating mechanism mounted on the closure plate it is obvious that modifications may be made in which the mechanism is mounted in the receptacle, and the closure plate may assume various positions, according to the use contemplated of the receptacle.

As the closure cannot be moved except upon the operation of internal electrically controlled mechanism, it will be seen that pilfering or tampering with the receptacle is effectively prevented.

When the closure plate 24 swings on its trunnions 33 to the tilted open position of Fig. 7, the electro-magnets 43 and 51 become de-energized, as heretofore described, and the locking bolt 34 falls by gravity to its forward position in which the spring-urged locking pin 46 enters the opening 45 in the locking bolt to retain the bolt against longitudinal displacement. When the closure plate is subsequently swung back to its closed horizontal position, the locking bolt displaces the resilient keeper 38 and engages above the hooked lower end of the keeper to again lock the closure plate in closed position.

What I claim as new and desire to secure by Letters Patent is:

1. In a receptacle, the combination with a casing, of a pivotally mounted gravity-opened closure for said casing, a locking member mounted on the closure and movable into engagement with a part on the casing to lock the closure, an electromagnet mounted on the

closure and cooperating with an armature to retract said locking member out of locking position, a retaining member normally engageable with said locking member to prevent movement out of locking position, means including an electromagnet for releasing said retaining member to permit electromagnetic retraction of said locking member and subsequent fall of said closure, and conductors for said electro-magnets extending through the walls of said casing.

2. In a receptacle, the combination with a casing, of a pivotally mounted gravity-opened closure for said casing, a locking member mounted on the closure and movable into engagement with a part on the casing to lock the closure, an electromagnet mounted on the closure and co-operating with an armature to retract said locking member out of locking position, a retaining member normally engageable with said locking member to prevent movement out of locking position, means including an electromagnet for releasing said retaining member to permit electromagnetic retraction of said locking member, and means operated by the opening fall of the closure for deenergizing said electromagnets.

3. In a receptacle, the combination with a casing having an upper coin receiving opening and a bottom coin discharge opening, a gravity-opened closure pivoted to said casing and normally closing said discharge opening, a locking member for normally locking said closure, electromagnetic means for retracting said locking member out of locking position to permit said closure to tilt and discharge the contents of the receptacle and a container disposed below said casing and receiving the coins discharged from said casing on the gravity opening of the closure.

4. In a receptacle, the combination with a casing having an upper receiving opening and a bottom discharge opening, a gravity-opened closure pivoted to said casing and normally closing said discharge opening, a locking member for normally locking said closure, electromagnetic means for retracting said locking member out of locking position to permit said closure to tilt and discharge the contents of the receptacle, and means operated by the tilting of said closure for breaking the current to said electromagnetic means.

5. In a receptacle, the combination with a casing, of a pivotally mounted gravity-opened closure for said casing, a locking member mounted on the closure and movable into engagement with a part on the casing to lock the closure, an electromagnet mounted on the closure and co-operating with an armature to retract said locking member out of locking position, contact members connected to said electromagnet and movable with the closure, contact terminals in the casing co-operating with said contact members to con-

nect said electromagnet with a current source for the retraction of said locking member, whereby the opening fall of the closure will separate the contact members and terminals to open the supply circuit.

6. In a receptacle, the combination with a casing, of a closure for said casing, a locking member movable to lock the closure and having a transverse opening, a bracket having an aperture in which said locking member is slidably mounted and guided, an electromagnet cooperating with an armature to retract said locking member out of locking position, a locking pin slidably mounted in 15 said bracket to enter said bracket aperture and adapted to normally enter said opening in the locking member to prevent movement of said locking member out of locking position, and an electromagnet cooperating with 20 an armature to withdraw said locking pin out of engagement with said locking member, whereby said locking member can be electro-magnetically retracted.

7. In a receptacle, the combination with 25 a casing, of a closure for said casing, a locking member movable to lock the closure, an electromagnet for retracting said locking member out of locking position, means for supporting said casing including a stationary 30 terminal block having connection with a source of current, a terminal block movable with the casing and having connections to said electromagnet, said terminal blocks co-operating to establish a circuit to said electromagnet and permitting removal of said casing terminal block off of said stationary terminal block, thereupon preventing actuation 35 of said locking member.

8. In a receptacle, the combination of a 40 casing having a movable closure, electro-magnetic means within said casing for opening said closure, a terminal member movable with the casing and having connection with said electro-magnetic means, and means for 45 supporting said casing including a stationary terminal member having connection with a source of current and being detachably engageable with said first-named terminal member, said terminal members co-operating 50 to establish a circuit to said electro-magnetic means and being detachable upon the removal of said casing from its normal supported position to prevent actuation of said electro-magnetic means.

9. The combination of a movable locking 55 member, a member engaged by said locking member when said locking member is in locking position, electro-magnetic means for retracting said locking member out of locking position, a retaining member normally engageable with said locking member to prevent movement of said locking member out of locking position, a second electro-magnetic means for retracting said retaining member 65 out of engagement with said locking mem-

ber, and circuit-closer means for controlling the successive operation of said two electro-magnetic means to move said locking member out of locking position and for preventing the operation of said first-named electro-magnetic means until said second-named electro-magnetic means has been operated, whereby to prevent binding of the mechanism.

In testimony whereof I affix my signature.

MAURICE J. DU FEAU.
